UNITED STATES PATENT OFFICE.

GEORGE WASHINGTON RANDALL, OF BOSTON, MASSACHUSETTS.

DOOR-CHECK.

SPECIFICATION forming part of Letters Patent No. 349,604, dated September 21, 1886.

Application filed May 23, 1885. Serial No. 166,426. (No model.)

To all whom it may concern:

Be it known that I, GEORGE WASHINGTON RANDALL, of Boston, in the county of Suffolk, of the Commonwealth of Massachusetts, have 5 invented a new and useful Improvement in Door-Holders; and I do hereby declare the same to be described in the following specification, and represented in the accompanying drawings, of which—

10 Figure 1 is a front elevation of a door-frame and door with my invention applied to the latter. Fig. 2 is a front view, Fig. 3 a side elevation, and Fig. 4 a vertical and longitudinal section, of the door-holder, such figures being on an enlarged scale with reference to that of Fig. 1.

The nature of my invention is duly defined in the claim hereinafter presented.

In such drawings, A denotes a tube provided with four ears, a, extending from it laterally, and being for fastening it to the front face of a door, B, by means of headed screws going through such ears and screwed into the door.

25 In the front of the tube or case A there is a long slot, b, which opens through the upper end of the tube or case, and has one edge serrated, or formed with a range of teeth, as shown at c. Extending lengthwise through 30 the said tube is a spindle or rod, C, provided at its lower end with a foot, d, having rubber or leather or other suitable frictional bottoming, e.

Within the case and on the rod is a shoulder, f, and resting on the shoulder and encompassing the rod is a spiral spring, D, above and on which is a tube or sleeve, E, that is concentric with and to slide on the rod. When in its highest position, the tube 40 E butts against a head or shoulder, h, fixed or screwed on the rod at its top.

A handle, i, extends from the tube E at its upper end, such tube at its lower end being provided with a tooth, k, projecting from it, and triangular in its transverse section. This tooth is to engage with the serrations of the slot b, the said slot being wide enough to allow of the tooth being turned into or out of engagement with such serrations.

50 In Fig. 1 the door is shown at B, its frame

at F, and the door-holder at H, there being at and projecting from and secured to the lower part of the door a bracket or guide, I, for the rod to slide through.

After having opened the door to any desired extent the handle i is to be forced downward, so as to cause the foot d to rest upon the floor, after which the handle is to be pressed farther downward to cause the sleeve E to compress the spiral spring to the necessary degree. The handle should next be moved so as to turn the sleeve laterally and cause its tooth to engage with the rack or series of teeth of the slot b. The spring will then press the rod C downward to cause its 65 foot to bear with sufficient friction on the floor to hold the door open.

At the upper end of the slot b, and leading laterally out of it, is a notch, l, which, formed in the tube A, serves to receive the tooth, in 70 order to keep the rod raised out of contact with the floor when such may be desirable.

This door-holder is very efficient in practice.

I do not claim a door-check constructed as represented in either of the United States 75 Patents Nos. 198,931 and 224,092, for neither of the door-checks of such patents have, like mine, a means of increasing the downward pressure of the spring, the spring of the door-check shown in Patent No. 198,931 being simply to depress the rod with a uniform pressure, and the spring of the door-check shown in Patent No. 224,092 being simply to elevate the rod, whereas in my door-check the spring 80 operates to depress the rod, and is provided with means of increasing the downward pressure as occasion may require—that is to say, there are to the rod and spring and their supporting tube the sleeve E and its tooth and the toothed slot in the tube A. Nor do I 85 claim a door-check—such as shown in United States Patent No. 155,158—in which the vertical slide carrying a curved arm having the roller is not revoluble in the case, and the slide that carries the spring-case is revoluble, 90 but is susceptible of vertical movements only, like the slide.

I claim—

The door-holder consisting of the guide-tube A, slotted, and having serrations in one 100

side and a notch at the top of the slot, the cylindrical rod C, having the shoulders f and h; and the frictional foot d, the sleeve E, provided with the handle i and tooth k, and 5 adapted to slide lengthwise and turn laterally on the upper part of the rod C, and in the guide-tube A, and the spring D, around the

rod between the sleeve and the shoulder f, as set forth.

GEORGE WASHINGTON RANDALL.
